UNITED STATES PATENT OFFICE.

CHARLES J. INGERSOLL, OF HOUSTON, TEXAS.

CLOTHES-PIN.

1,059,610.

Specification of Letters Patent.

Patented Apr. 22, 1913.

Application filed June 23, 1911. Serial No. 634,963.

To all whom it may concern:

Be it known that I, CHARLES J. INGERSOLL, citizen of the United States, residing at Houston, in the county of Harris and State of Texas, have invented certain new and useful Improvements in Clothes-Pins, of which the following is a specification.

This invention comprehends certain new and useful improvements in that type of clothes pins which are so constructed as to automatically lock themselves against accidental disengagement from the clothes line when placed in position thereon, and the invention has for its primary object to produce a pin of improved construction and increased strength.

With this and other objects in view as will more fully appear as the description proceeds, the invention consists in certain constructions, arrangements and combinations of the parts that I shall hereinafter fully describe and claim.

For a full understanding of the invention, reference is to be had to the following description and accompanying drawings, in which:

Figure 1 is a perspective view of one form or embodiment of the invention, the two clamps being shown broken apart and separated. Fig. 2 is a similar view of another form of the device.

Corresponding and like parts are referred to in the following description and indicated in all the views of the drawings by the same reference characters.

The improved device is formed from a single piece of wire and comprises a clamping jaw bent to form a bow 3 for the jaw 2, outer spring members 4 for the jaws and inner spring members 5 that are preferably slightly divergent near their outer portions to provide an entrance mouth wherein the clothes line indicated at 6, may be easily entered. After the wire has been turned inwardly from the members 4 to form the inner members 5 of the jaws 2, one of the ends of the wire is continued and bent into a loop through which one of the portions 5 is extended and whereby it is supported. The por-

tion 5 is extended in substantially parallel relations to the line 6 as represented at 9^a and terminates in an eye 11 connected into a ring 12 slidably mounted upon the line 6. If preferred, an open loop 10 may be substituted for the eye 11 and ring 12, as shown in Fig. 1. By this simple means the portion 9^a is supported from lateral movement or displacement by the loop. The loop may be extended to form a secondary jaw as shown in Fig. 2 if preferred. By this simple means the main jaw is firmly supported and lateral displacement of the extension 9^a prevented.

The device being secured to the clothes line by its attaching ring 12 as above described, the jaws 5 are in position to be engaged over the clothes line and thus support the garments, the loop 3 bearing upon the outer face of the garment and holding them in position while at the same time preventing the jaw from downward displacement relative to the line.

The improved device is simple in construction, can be inexpensively manufactured and is retained in slidable and adjustable relations to the line and cannot therefore become lost or displaced while at the same time is at all times in position for instant use.

Having thus described the invention, what is claimed as new is:

A clothes pin of the character described formed from a single piece of wire and embodying oppositely directed clamping members each containing co-acting jaws connected by a loop, the clamping members being connected by parallel portions, one of the parallel portions being extended through the loop of one clamping member to hold the parts in relative position and thence extended to form means adapted to slidably connect the extended portion to a clothes line.

In testimony whereof, I affix my signature in presence of two witnesses.

CHARLES J. INGERSOLL. [L. S.]
Witnesses:

JAMES A. BREEDING,
CHARLES HEILL.
